UNITED STATES PATENT OFFICE.

WALTER C. BROOKS, OF SPRINGFIELD, MASSACHUSETTS.

TOOL-HOLDER.

1,330,514.

Specification of Letters Patent.

Patented Feb. 10, 1920.

Application filed May 21, 1919. Serial No. 298,766.

To all whom it may concern:

Be it known that I, WALTER C. BROOKS, a citizen of the United States of America, and a resident of Springfield, in the county 5 of Hampden and State of Massachusetts, have invented a new and useful Tool-Holder, of which the following is a specification.

My invention relates to improvements in 10 holders for lathe-turning and -boring tools and the like while being ground, and consists of a block of peculiar construction and provided with tool-clamping means, all as hereinafter set forth.

15 The primary object of my invention is to produce a comparatively simple and inexpensive, compact, convenient, strong and durable holder, which is capable of being secured in place either by means of a bolt 20 passing through the body of said holder, or by magnetic means, and which at the same time is adapted to hold securely in the proper manner at the correct angle any one of various cutting tools while the tool is 25 being ground.

Other objects and advantages will appear in the course of the following description.

I attain the objects and secure the advantages of my invention by the means illustrated in the accompanying drawings, in which—

30 Figure 1 is a top plan of a tool holder which embodies a practical form of my invention; Fig. 2, a side elevation of said holder; Fig. 3, an elevation of the boring-tool end of the holder, showing such a tool in place therein; Fig. 4, an elevation of the turning-tool end of the holder, showing such a tool in place therein, and, Fig. 5, a vertical 35 section through the body or block of the holder, taken through the transverse passages therein.

Similar reference characters designate similar parts throughout the several views.

40 Although the holder block more often rests on some one of its side faces than on its bottom while in use, for the purpose generally of this description, such block is assumed to rest on such bottom, as shown; 45 and the tools represented as being secured in the holder, in Figs. 3 and 4, may not be disposed to the best advantage for grinding, but their presence serves to illustrate clearly the manner in which they are held in place.

50 My tool holder comprises a block 1, a vertical clamp 2 mounted on a pin 3 and a

clamp screw 4 at one end of said block, a horizontal cross-piece 5 at the other end of said block, and a clamping screw 6 tapped into and through such cross-piece. 60

The block 1 has a top and bottom which are parallel with each other, sides which converge from the central horizontal plane of said block toward said top and bottom, an end that is at right-angles to said top and bottom, and an end that inclines downwardly and outwardly from said top. There is a transverse, V-shaped groove 7 in the perpendicular end near the top of the block 1, and a channel 8 in the center of the inclined 70 or oblique end of said block. The channel 8 extends from the top of the block 1 to the bottom of said block on to a cut-away portion 9 thereof at the lower end of said channel, and the latter is rectangular in cross 75 section. A vertical passage 10 extends through the block from top to bottom, and similar passages 11—11 extend through said block from the inclined faces on one side to the inclined faces on the other side, all of 80 said passages intersecting within the block, as best shown in Fig. 5. Each passage 11 extends from an upper inclined face on one side to the lower inclined face on the opposite side of the block, and is at right-angles 85 to such faces, which latter are parallel with each other. The passage 10 is at right-angles to the top and bottom of the block. These passages are designed to receive bolts to such faces, which latter are parallel with 90 each other. The passage 10 is at right-angles to the top and bottom of the block. These passages are designed to receive bolts for securing the block in place on the grinding-machine, as presently will be more fully explained, and should be located far enough from the oblique end of the block so that a bolt (not shown) in the passage 10 and a tool (as 12) in the channel 8 do not interfere 95 with each other.

The pin 3 projects from the perpendicular end of the block 1, in the longitudinal, central, vertical plane and below the horizontal, central plane of said block, and the screw 4 is tapped into said block directly over said pin and above said last-named plane. The pin 3 is received in a hole 13, Fig. 3, in the clamp 2, which hole is near the lower end of said clamp and large enough to permit the 105 clamp to move to the extent necessary in the clamping operation. The screw 4 passes through the approximate center of the clamp 2, and may be rotated freely therein. The upper end of the clamp 2 is adjacent to the 110 groove 7. The clamp 2 has on the inner side at the top and bottom, respectively, pro-

jections or ribs 14 and 15, the latter being designed to bear against the contiguous end of the block and the former to bear on a tool (as 16) in the groove 7, when the screw 4 is tightened.

The tool 16, shown in Fig. 3 and having a portion of its stem broken out, is an ordinary boring tool, and, when the same is to be ground, it is placed in the groove 7 and 10 properly adjusted therein, and the screw 4 is tightened to force the rib 14 of the clamp 2 hard against said tool, the rib 15 of said clamp meanwhile bearing directly on the block 1. Ready means are thus 15 afforded for properly positioning and securely holding the tool 16. Said tool is released by loosening the screw 4 and removed by withdrawing it from the groove 7. The pin 3 prevents the clamp 2 from turning 20 on or with the screw 4 during the tightening and loosening operations.

The cross-piece 5 has the general form of an inverted T. Said cross-piece spans the channel 8, and the lateral arms of the cross-piece are secured to the block 1 by means of 25 two screws 17 which pass through such arms into the contiguous end of said block. The screw 6 is carried by the upstanding arm of the cross-piece 5. Any tool not too large 30 to enter the channel 8 and be received behind the cross-piece 5 may be secured in place in said channel. In other words, the tool in question need not fill the channel 8.

The tool 12, shown in Fig. 4 and which is 35 an ordinary turning tool, is slipped into the channel 8 and secured therein by the screw 6, when it is desired to grind such tool. The tool 12 is placed with one side against one 40 amount of projection before tightening the screw 6 against the contiguous side thereof. Said tool must, of course, be so placed in the groove 8 that the sharp edge of the tool is in a plane parallel with that of the top 45 of the block 1. Upon loosening the screw 6 the tool 12 can be slipped out of the groove 8. Thus ready means are provided for 50 properly positioning and securely holding the tool 12.

For grinding the tool 16, the block 1 is 55 placed on the oblique face thereof which is the more remote from but on the same side with the cutting end and the part of said tool that is to be ground. The block is held 60 in this position on or in the grinding machine, while the tool is ground, by magnetic means, or by a bolt passing through the passage 11 that opens through the aforesaid oblique face, as the case may be. The angle 65 of this face corresponds with or determines the angle of the ground part of the tool 16.

For grinding the tool 16, the block 1 is first placed on the oblique face thereof which 70 is most remote from the side of the cutting 75 part of said tool that is to be ground first.

The block is held in this position in the grinding machine, while the aforesaid side of the cutting part of the tool is ground, by magnetic means, or by a screw passing through the passage 11 that opens through the 70 aforesaid oblique face. The block is then turned over and placed on the oblique face which is most remote from the side of the cutting part of the tool that is to be ground next. The block is held in this latter 75 position, while the said side of the cutting part of the tool is ground, by magnetic means, or by a screw passing through the other passage 11. The angles of the oblique faces of the block correspond with or determine the angles of the ground sides of the cutting part of the tool 12.

If it be desired to grind off the sharp edge of the tool 12, or to grind the ridge of a tool of this character, the block is set on its 80 bottom in the grinding machine and held by magnetic means or by a bolt passing through the passage 10. The angle of the oblique end of the block 1 positions the tool with its cutting edge or ridge parallel with 85 the bottom of said block, or in such a manner that such edge or ridge can be ground so as to be parallel with said bottom.

The foregoing description contemplates 90 mounting the block 1 on a horizontal, supporting member of the grinding machine, but said block might be mounted otherwise, if necessary, in order to meet other conditions, as in a machine the work-holding and grinding elements of which are arranged 95 differently relatively from those in an ordinary grinder.

More or less modification and change may be made in the shape, size, construction, and arrangement of some or all of the parts of 100 my tool holder, without departing from the spirit of my invention, or exceeding the scope of what is claimed.

What I claim as my invention, and desire 105 to secure by Letters Patent, is—

1. A tool holder, of the class described, comprising a block the sides of which converge from the approximately central horizontal plane toward the top and bottom of 110 said block, said top and bottom being parallel, one end of said block being at right-angles to said top and bottom, and the other end of said block being oblique, and tool-clamping means at such ends.

2. A tool holder, of the class specified, 115 comprising a solid block flat on the top and bottom and having sides which converge from the approximately central horizontal plane of said block toward said top and bottom, said block having bolt-receiving passages which open through the four converging faces of said sides, and end tool-clamping means.

3. A tool holder, of the class described, 120 comprising a solid block, the top and bot-

- tom of which are flat and parallel, said block having a bolt-receiving passage which opens through said top and bottom, and means to clamp a tool to one end of said block.
5. 4. A tool holder, of the class described, comprising a solid block the sides of which converge from the approximately central horizontal plane toward the top and bottom of said block, said top and bottom being parallel, and said block having bolt-receiving passage which open through the converging faces of said sides and through said top and bottom, and end tool-clamping means.
10. 5. A tool holder, of the class described, comprising a block having oblique sides and a transverse approximately V-shaped groove in one end, and clamping means at such end adapted to engage a tool placed in said groove.
15. 6. A tool holder, of the class described, comprising a block having oblique sides and a transverse approximately V-shaped groove in one end, and provided at such end with a pin, a clamp mounted on said pin, and a screw passing through said clamp and tapped into said block, the free end of said clamp being adjacent to said groove.
20. 7. A tool holder, of the class described, comprising a block having oblique sides and an oblique end and a longitudinal channel in such end, and clamping means at such end
- adapted to engage a tool placed in said channel.
8. A tool holder, of the class described, comprising a block having oblique sides and an oblique channeled end, a cross-piece secured to such end across the channel therein, and a screw tapped into said cross-piece and arranged with its inner end adjacent to said channel.
40. 9. A tool holder, of the class described, comprising a block the sides of which converge from the approximately central horizontal plane toward the top and bottom of said block, said top and bottom being parallel, one end of said block being perpendicular to said top and bottom, and having a transverse groove therein, and the other end of said block having a downward and outward inclination from said top, and also having a channel extending lengthwise thereof, a pin and screw projecting from said first-named end, a clamp mounted on said pin and screw and adapted to engage a tool in said groove, a cross-piece at said second-named end, and a screw carried by said cross-piece and adapted to engage a tool in said channel.
